UNITED STATES PATENT OFFICE.

CHARLES R. PRATT, OF MONTCLAIR, NEW JERSEY, ASSIGNEE TO THE UNIVERSAL SPEED CONTROL COMPANY, A CORPORATION OF NEW YORK.

ELECTRIC CONTROL FOR DELIVERY OF POWER.

1,159,082.

Specification of Letters Patent.

Patented Nov. 2, 1915.

Application filed March 13, 1910, Serial No. 549,841. Renewed March 31, 1915. Serial No. 18,412.

To all whom it may concern:

Be it known that I, CHARLES R. PRATT, a citizen of the United States, residing at Montclair, in the county of Essex and State of New Jersey, have invented certain Improvements in Electric Control for Delivery of Power, of which the following is a specification.

This invention relates to the delivery of power, such as from a generator like an engine motor, or from transmitting means employed to vary the speed and direction of rotation, known as variable power transmission, like a fluid gear.

The objects of the invention are to secure such delivery of power through the rotation of a delivery member at desired speed, even under varying loads or other conditions; to do this by keeping the rotating member in positive synchronism with a rotating pilot member under no load and whose speed can be exactly controlled; to control said pilot member, and thus the delivery of power, by electric means which shall be practical and efficient; to employ for this purpose a pair of electric pilot motors; to provide means for varying the speeds of said motors, and for varying them oppositely at the same time; to obtain very finely graduated steps of variation; to transmit the motion of the said pilot motors to two elements engaging an intermediate differential element, and thus controlling the speed thereof; to thus secure a pilot speed; to transmit said pilot speed to one of a second pair of elements engaging an intermediate differential element, the other engaging element being connected to the fly-wheel of the engine or motor member of the fluid gear, and the intermediate member being adapted to transmit motion to the throttle of the engine or swinging member of the fluid gear; to thus secure an electric and automatic control of the delivery of power, actuated by said power delivery itself independent of load, leakage or the like, and to obtain other advantages and results as may be brought out in the following description.

Referring to the accompanying drawings, in which like numerals of reference indicate corresponding parts in each of the several

figures, Figure 1 is a horizontal section upon line 1—1 of Fig. 3, of the gearing of my improved control; Fig. 2 is a diagrammatic plan of the pilot motors and their connections to the rheostat; Fig. 3 is a side view 55 of the gearing shown in Fig. 1 with the side wall of the casing cut away, as on line 2—2 of Fig. 1; Fig. 4 is a plan view of my improved control applied to a fluid gear inserted between a gas engine and the driving 60 pulley, and Fig. 5 is a partial side elevation of the same.

In said drawings, 10 indicates a suitable casing or support in which is journaled a shaft 11 which is driven from the delivery 65 end of any power delivery means desired to be controlled, as for example the fly wheel of a steam engine, the armature shaft of a motor, or the shaft of the motor member of a fluid gear such as shown in the patent of 70 Holbrook F. J. Porter, issued March 7, 1911, No. 985,835. For convenience and greater definitiveness, I have shown my invention applied to a fluid gear, see Figs. 4 and 5, and will describe it in such application, although it should be understood that the control can be used in many other ways.

At its end within the casing 10, see Fig. 1, the shaft 11 has a worm 12 which meshes into the periphery 13 of a worm wheel 14, 80 said worm wheel being loose upon a shaft 9 shown as journaled transversely of the casing 10. Upon one side of said worm wheel 14 are bevel gear teeth 15, and opposite said gear teeth 15 are other bevel gear teeth 16 85 upon the side of a gear wheel 17 also mounted loose upon the said shaft 9. Between the two wheels 14 and 17 is a spider 18 keyed to the shaft 9, and having at its periphery upon radial pivots 19 a series of floating differential gears 20 which mesh with the gear teeth 15 and 16 described. The shaft 9 is connected at its outer broken end 21 in any suitable manner with the control member of the power delivering means, as for example the 90 throttle of a steam engine, the rheostat arm or lever of a motor, or the carrier for the swinging cylinder of a fluid gear. In the Porter fluid gear above referred to, connection would be made from shaft 21 either to 100

cross arm 71 or to hand wheel 691 of said Porter patent, and in Figs. 4 and 5 I have shown connection to a hand lever 75 which replaces said cross arm.

With the construction above described, it will be understood that the power delivery is under positive and sensitive control by means of the gear wheel 17 described. If said gear 17 is rotated clockwise as viewed in Fig. 3, the shaft 11 standing still, obviously the floating gears 20 will also be rolled around in clockwise direction and the shaft 9 correspondingly rotated. The rotation of this shaft 9 may be employed in any manner common to mechanics to turn the cylinder carrier of the pump member of the fluid gear, such turning being in proper direction to start the delivery of power from the fluid gear. In Figs. 4 and 5, for example, the shaft 9 is shown provided at its outer end with a small gear 76 meshing into a large gear 77 upon a suitable shaft having bearings 78, 78, and having also fast upon itself an arm 79 adapted to stand parallel with the hand lever 75 of the swinging carrier of the pump member 80 of the fluid gear, said arm being connected to said lever by a link 81. As the hand lever 75 is swung, power will be transmitted from the pump member 80 to the motor member 82 and delivered therefrom through the shaft 83 thereof having the driving pulley 84. This delivery will rotate the shaft 11, referring now again to Fig. 1, in such a way as to effect rotation of the worm wheel 14 in a direction opposite to that of the gear wheel 17, or against the hands of a clock as viewed in Fig. 3. Obviously such rotation of the worm wheel 14, which has been serving as a fulcrum for the floating gears 20, will retard the revolution of the spider frame 18 carrying said floating gears and hence the rotation of the shaft 9 and swinging of the cylinder carrier. When the cylinder carrier is swung to such a point that the worm wheel 14 rotates at the same speed as the gear wheel 17, there will be no rotation of the shaft 9, and consequently no swinging of the cylinder carrier in either direction. If the cylinder carrier were swung too far, or by variation in the load or work being done the motor member of the fluid gear should speed up, so that the worm wheel 14 rotated faster than the gear wheel 17, the spider 18 would obviously be turned in the opposite direction or against the hands of a clock, and with it the shaft 9, thus swinging the cylinder carrier back to lessen the speed. Obviously the device therefore automatically holds the cylinder carrier at just that point where the delivery speed of the fluid gear turns the worm wheel 14 in synchronism with the gear wheel 17, and hence said gear wheel 17 is a pilot wheel controlling the fluid gear. It will be noted

that this control is absolutely independent of leakage in the fluid gear or variations in the load from any reason whatever.

For determining the speed of the pilot wheel 17, I employ two pilot motors 30, 31, 70 adapted to rotate their armature shafts 32 and 33 in opposite directions. These armature shafts have worms, as 35, respectively engaging worm-wheels 36, 37 mounted loosely on a transverse shaft 38 of the casting 10. Said worm wheels 36, 37 are at their adjacent sides connected to fulcrum gears 40, 41, between which is a gear 39 on the shaft 38 provided inside its rim with floating gears 42 mounted upon radial pivots 43 80 and engaging at their opposite peripheral edges said gears 40, 41. The gear 39 meshes at its periphery with the pilot gear 17, or is otherwise connected thereto.

Obviously, if the pilot motors 30, 31 are 85 rotated at the same speed in opposite directions, there will be no rotation of the gear 39, and consequently no speed imparted to the pilot wheel 17. If, however, the speeds of the two worm wheels 36, 37, and consequently two gears 40, 41, vary, the carrier gear 39 will be rotated according to the amount of such variation, thus rotating the pilot wheel 17 accordingly. I therefore provide means for controlling the two pilot motors 30, 31 with respect to each other, as will next be described. This control of the pilot motors 30, 31 is secured by varying the resistances of their field circuits by means of rheostats. In Fig. 2, 51, 52, etc., are the contact blocks of a series of steps of the resistance of a rheostat, said steps dividing the whole resistance of the rheostat into as many parts as desired. The end contact blocks of the series are connected by wires 53, 54 to opposite terminals of the fields of the two pilot motors. A continuous contact strip 55 is adjacent to the series of contact blocks 51, 52, etc., and this contact strip is connected by a wire 56 to the generator or other source of electric energy. A brush 57 resting both upon the strip 55 and opposite contact blocks 51, 52, etc., is carried by an arm 58 of a hand wheel 59, so that the rheostat can be operated by said hand wheel in the following manner. As the wheel 59 is turned, for instance to swing the arm 58 from its central position to the left as viewed in Fig. 2, a smaller portion of the current will pass through wire 53 to pilot motor 30 and a larger amount through wire 54 to pilot motor 31. This varies the fields of said motors, giving them different speeds, and according as the arm 58 is swung more or less, the difference in speeds of the two pilot motors is greater or less. Consequently, the gear 39 rotates faster or slower, and thus the pilot wheel 17 can be given a desired speed.

It will be observed that the swinging of 130

the single arm 58 varies the fields of both motors, equally and simultaneously. In other words, the fields of two motors are varied simultaneously by means of the same 5 rheostat, resistance and contacts.

Opposite the rheostat 50 described, is a second series of contact blocks, 61, 62, etc., sub-dividing the entire resistance of a rheostat 60 into as many divisions as desired, 10 the whole resistance of the rheostat 60 being equal to that of a single step of the first-mentioned rheostat 50. The end contact blocks of the said second series of steps are connected by wires 63, 64 to the other terminals 15 of the fields of the pilot motors from those to which the rheostat 50 is connected, and a contact strip 65 is connected by a wire 66 to the second terminal of the electric generator. A brush 67 is carried by an arm 68, 20 pivoted upon the same center 70 with the arm 58, and adapted to be turned by a wheel 69 concentric with wheels 59. Thus, after the brush 57 of the main rheostat 50 has been brought to the position which most nearly 25 gives the pilot speed desired, finer adjustment is had by means of the arm 68 of the auxiliary rheostat 60, which enables each step of the main resistance to be divided into parts. It will be noted that the two rheostats are connected with the pilot motors in 30 series. Wires 71 and 72 denote the armature circuit, being branched for each pilot motor, as necessary. The ends of the armature shafts 32, 33 of the two pilot motors are supported and journaled in posts 73, 74, one of 35 said posts, as 74, providing also a bearing for the end of the shaft 11.

Obviously, instead of varying the fields of the pilot motors, as described, their armature circuits could be varied by the same means and in substantially the same way. Other changes involving only mechanical skill and a knowledge of the prior state of the art, and associated arts, could be made without 45 departing from the spirit and scope of my invention.

It will be understood that in Fig. 4, 85 indicates a gas engine and 86 the fly wheel thereof, connected direct to the pump member 80 of the fluid gear.

Having thus described the invention, what I claim is:

1. A delivery control for power delivery means, comprising a pilot member, means for connecting and synchronizing the delivery member of said power delivering means with said pilot member, two pilot motors, and means for transmitting to said pilot member from said pilot motors a speed proportional to the algebraic sum of the speeds of the said motors.

2. A delivery control for power delivery means, comprising a pilot member, means for connecting and synchronizing the delivery member of said power delivering

means with said pilot member, two pilot motors, means for simultaneously and oppositely varying the speeds of said pilot motors, and means for transmitting to said pilot member from said pilot motors a speed 70 proportional to the algebraic sum of the speeds of the said motors.

3. A delivery control for power delivery means, comprising a pilot wheel, means for connecting and synchronizing the delivery 75 member of said power delivering means with said pilot wheel, two pilot motors, means for transmitting to said pilot member from said pilot motors a speed proportional to the algebraic sum of the speeds of said motors, 80 and means for simultaneously varying said pilot motors.

4. A delivery control for power delivery means, comprising a pilot member, means for connecting and synchronizing the delivery 85 member of said power delivering means with said pilot member, a driving wheel for driving said pilot member, a floating gear on said driving wheel, engaging members one at each side of said floating gear, and independent means for driving each of said engaging members.

5. A delivery control for power delivery means, comprising a pilot member, means for connecting and synchronizing the delivery 90 member of said power delivering means with said pilot member, a driving wheel for driving said pilot members, a floating gear on said driving wheel, engaging members one at each side of said floating gear, independent means for driving each of 95 said engaging members, and means for simultaneously varying both said driving means oppositely.

6. A delivery control for power delivery 100 means, comprising a pilot member, means for connecting and synchronizing the delivery member of said power delivering 105 means with said pilot member, a driving wheel for driving said pilot member, bevel 110 gears with radial axes on said driving wheel, driving bevel gears on each side of said driving wheel in axial alinement therewith, independent means for driving each of said driving 115 wheels, and means for varying both said driving means simultaneously.

7. A delivery control for power delivery means, comprising a pilot member, means for connecting and synchronizing the delivery 120 member of said power delivering means with said pilot member, a driving wheel for driving said pilot member, a floating gear on said driving wheel, engaging members one at each side of said floating 125 gears, motors one for driving each of said engaging members, and means for varying the motors oppositely and simultaneously.

8. A delivery control for power delivery means, comprising a pilot member, means for connecting and synchronizing the de- 130

- livery member of said power delivering means with said pilot member, a driving wheel for driving said pilot member, a floating gear on said driving wheel, engaging members one at each side of said floating gear; motors adapted to each drive one of said members in the opposite direction from the other, and means for varying both said motors simultaneously.
10. 9. The combination with a pilot wheel, of an equalizing gear having a differential element and opposite engaging elements, means for transmitting motion from said differential element to the pilot wheel, motors each adapted to drive one of said engaging elements, and means for varying said motors oppositely and simultaneously.
10. The combination with power delivering means and a power control therefor, of floating gears each adapted to rotate upon its center and to move along a given path, a pilot wheel in engagement with said floating gears, a second wheel in engagement with said floating gears and connected to the power delivering member, means for imparting revolution of said floating gears to the power control of the power delivering device, a driving wheel adapted to engage said pilot wheel, planetary gears mounted on said driving wheel, fulcrum gears one at each side of said planetary gears, motors one for driving each of said fulcrum gears in opposite directions one from the other, and means for controlling said motors simultaneously.
11. The combination with a power delivering device and a power control therefor, of floating gears each adapted to rotate upon its center and to move along a given path, a pilot wheel in engagement with said floating gears, a second wheel in engagement with said floating gears and connected to the power control of the power delivery device, a driving wheel adapted to engage said pilot wheel, planetary gears mounted on said driving wheel, fulcrum gears one at each side of said planetary gears, motors one for driving each of said fulcrum gears in opposite directions one from the other, and means for controlling said motors simultaneously.

CHARLES R. PRATT.
